UNITED STATES PATENT OFFICE.

SALLIE R. MCLEAN, OF GLENDALE, OHIO.

OUTER GARMENT.

1,184,255.

Specification of Letters Patent. Patented May 23, 1916.

Application filed September 20, 1915. Serial No. 51,625.

To all whom it may concern:

Be it known that I, SALLIE R. MCLEAN, a citizen of the United States, residing at Glendale, in the county of Hamilton and State of Ohio, have invented certain new and useful Improvements in Outer Garments, of which the following is a specification.

My invention relates to outer garments, especially protective or waterproof garments.

It is the object of my invention to provide a protective or waterproof garment of novel construction so arranged as to afford protection for those parts of the wearer's clothes most exposed to rain or splashing and at the same time afford ample ventilation for preventing discomfort of the wearer.

20 The invention will be further readily understood from the following description and claims, and from the drawings, in which latter:

Figure 1 is a front elevation of my improved device, showing the arm-sections spread. Fig. 2 is a side elevation of the same. Fig. 3 is a central vertical section of the same, taken on the line 3—3 of Fig. 1. Fig. 4 is a central vertical section of the same taken on the line 4—4 of Fig. 2, partly broken away. Fig. 5 is an inside elevation, partly broken away, showing the arm-section closed. Fig. 6 is a similar view of a portion of the same, exposing the fastening means. Fig. 7 is an inside view of one of the skirt-pocket flaps, showing the same closed. Fig. 8 is a similar view of the same, showing the flap partly open. Fig. 9 is an enlarged sectional view of the skirt-section 35 exposing the flap-fastening means and staying means for the skirt-pocket; and, Fig. 10 is an enlarged view of the gathered portion of the skirt-pocket, partly broken away.

11 represents the coat or body-portion, 45 and 12 the skirt of my improved garment, connected through the medium of a belt 13, from which straps 14 connect with the skirt, and straps 15, 16, connect with the coat.

The coat comprises a front-section comprising the sections 21, 22, a back section 23, and sleeve-sections 24, 25, the sections being connected at their tops by the shoulder cape-portion 26. The coat is shown as arranged to open and close between the front-sections by means of a series of snaps 27.

55 The coat is preferably cut low at the

neck, as shown at 30, being preferably suspended from a neck-strap 31, this suspension being preferably adjustable. The suspension is shown accomplished by means of straps 32 connecting with the neck-strap at their upper ends, as by being stitched thereto, and at their lower ends connecting with the cape-portion by means of buckles 33, the buckles being secured to the collar-band 65 34 of the cape-portion.

By my improved arrangement great freedom and ventilation is provided above the shoulders and at the neck of the wearer, the front of the neck-portion and upper chest- 70 portion of the wearer or clothes-parts covering the same being unobstructed.

The front-sections and sleeve-sections are separated by slits 36 and the back-section and sleeve-sections are separated by slits 37, 75 forming an opening 38 at each side of my improved garment between the front section and back-section, in which the arm of the wearer may normally hang to have movement, the sleeve-sections normally covering 80 said openings and normally lapping over the front and rear edges thereof. (See Figs. 2 and 3).

The wearer may wear the sleeve-sections open, for instance in mild weather or when 85 not exposed to rain or other precipitation, or the wearer may close the lower ends of the sleeve-sections about his arms. For accomplishing this I provide the side edges of the lower portions of the sleeve-sections with 90 snaps 41. When so closed, the inner faces of the upper portions of the sleeve-sections are preferably open, that is to say, the goods of my improved outer garment preferably does not extend into the arm-pit portions of the wearer, the upper portions of the sleeve-sections, however, preferably lapping over the upper portions of the front and back-sections of the coat, when the lower end of the sleeves are closed.

100 The width of the openings 38 may be adjusted by adjustment of the straps 16, which are shown adjustably secured to the front and back sections respectively by means of buckles 42, 43, secured to said front and back sections respectively.

The front sections are preferably provided with rearward extensions 45 and the back-section is preferably provided with forward extensions 46. When the straps 16 110 are adjusted to decrease the width of the openings 38, the extensions 45, and 46 may

be caused to lap at the respective sides of the garment.

The belt is a two-part belt, comprising the sections 13^a and 13^b, adjustable for length 5 at its front and back, as by means of front snaps 47 and rear snaps 48.

The skirt 12 comprises a pocket 51, in which the lower ends of the skirt portions of the outer skirt 52 and petticoat 53 of the 10 wearer's clothes may be received, thereby protecting the lower ends of the wearer's clothes from rain, splashing, and from contact by the shoes of the wearer with said clothes.

15 The height of the skirt-section of my improved garment is adjustable with relation to the coat-section thereof, accomplished in the present instance by means of passing the straps 14 through slits 54 in the belt 13, and 20 adjustably securing said straps in said slits, as by means of providing said straps with a plurality of snap socket-members 55 selectively coacting with a snap button-member 56. The adjustment of the belt at front 25 and rear insures that the straps shall properly hang at the respective sides of the wearer. The lower ends of the straps are suitably secured as by stitching, to the upper band 57 of the outer wall 58 of the 30 pocket 51 which surrounds the outer face of the skirt-portions of the wearer's clothes.

The inner wall 60 of the pocket of the skirt-member of my improved device is received within the lower ends of the skirt- 35 portions of the wearer's clothes. The outer and inner walls of said pocket-member are connected at their bottoms by a plurality of seams 61, 62, forming a reinforce band 63 around the lower end of the pocket-member. Stiffening strips 64, for instance of whale- 40 bone or steel, extend upwardly from the lower end of the pocket-member, being preferably crossed by the seam 61 and secured in the band 63, and serve the purpose of aiding in sustaining the inner wall of the pocket in upward relation. For further aiding in 45 supporting the inner wall of the pocket in upward relation, and providing yield to the stride of the wearer, the upper end of said inner wall is preferably provided at its rear portion with an elastically gathered portion 65, accomplished by a strip of rubber elastic webbing 66, tacked at its ends to said upper end of said pocket in separated relation, as at 67, 68, and having elastic movement in a channel 69 in said upper end. For further aiding in sustaining the inner wall of the pocket 51, I provide the same with adjustable flaps 71 arranged to 50 lengthen or shorten the circumference of the upper end of said inner wall of the pocket 51. The flaps are preferably located at the stiffening strips 60, the inner wall of the pocket 51 being provided with up and down slots 72, at the sides of which a plurality of 55

rows of snaps are located, instance as a plurality of rows of snap-sockets 73 with which a row of snap-buttons 74 selectively coact.

The location of the belt 13 with relation 70 to the shoulder or cape-portion of the coat may be made adjustable, accomplished in the present exemplification by means of interposing buckles 75 between the upper and lower sections of the straps 15. 75

Having thus fully described my invention, what I claim as new and desire to secure by Letters Patent, is:

1. In a garment of the character described, the combination of a neck-strap, a 80 shoulder cape-portion the upper end of which is spaced from said neck-strap, straps connecting said neck-band and shoulder cape-portion, and a front-section, a back-section and sleeve-sections extending downwardly from said cape-portion, said front-section and back-section having an opening therebetween at each side of said garment normally having said sleeve-sections there- 85 over.

2. In a garment of the character described, the combination of a shoulder cape-portion, a front-section, a back-section and a pair of sleeve-sections extending downwardly from said cape-portion, said front- 90 section and back-section having an opening therebetween at each side of said garment, the walls of said respective openings having extensions projecting toward each other at the lower portions of said sleeve-sections, 95 said sleeve-sections normally lapping over said extensions, and means for closing the lower ends of said sleeve-sections.

3. In a garment of the character described, the combination of a shoulder cape- 100 portion, a front-section, a back-section and a pair of sleeve-sections extending downwardly from said cape-portion, said front-section and back-section having an opening therebetween at each side of said garment, 110 said sleeve-sections normally lapping over the side walls of said openings, means for adjustably drawing said walls of said respective openings toward each other, and means for closing the lower ends of said re- 115 spective sleeve-sections.

4. In a garment of the character described, the combination of a coat-section, a skirt-section spaced from said coat-section and provided with a skirt-receiving pocket, 120 a belt, straps between said skirt-section and said belt, and adjusting means for said straps for adjusting the distance of said skirt-section from said belt.

5. In a garment of the character de- 125 scribed, the combination of a coat-section having a shoulder cape-portion and a front- section, a back section and sleeve-sections depending from said cape-portion, a belt, a skirt-section provided with a skirt-receiving 130

5 pocket, straps for suspending said skirt-section from said belt, said front-section and back-section having an opening therebetween at each side of said garment, an adjustable strap connecting the walls of each of said openings, adjustable straps between said last-named straps and said belt for adjusting the distance of said belt from said 10 cape-portion, and means for adjusting said first-named straps for adjusting the distance of said skirt-section from said belt.

6. In a garment of the character described, the combination of a skirt-receiving pocket comprising an outer wall surrounding the skirt of the wearer's clothes and an inner wall received within said skirt, and stiffening strips extending up and down along said inner wall and secured thereto for sustaining said inner wall in up and 20 down relation, the upper end of said inner wall provided with an elastic section and means connecting with said outer wall for suspending said pocket from the wearer.

7. In a garment of the character described, the combination of a skirt-receiving pocket comprising an outer wall surrounding the skirt of the wearer's clothes and an inner wall received within said skirt, said walls connected at their bottoms and extend-

ing upwardly, the upper end of said inner wall provided at its rear portion with an elastic section, and means connecting with said outer wall for suspending said pocket from the wearer.

8. In a garment of the character described, the combination of a skirt-receiving pocket comprising an outer wall surrounding the skirt of the wearer's clothes and an inner wall received within said skirt, said walls connected at their bottoms and extending upwardly, stiffening strips extending up and down along said inner wall and secured thereto for sustaining said inner wall in up and down relation, said inner wall provided with slits at said stiffening strips, said slits opening upwardly, the walls of said slits arranged to be placed in lapping relation, means for adjustably securing said walls of said slits in lapping relation, and means connecting with said outer wall for suspending 50 said pocket from the wearer.

In testimony whereof, I have hereunto signed my name in the presence of two subscribing witnesses.

SALLIE R. McLEAN.
